UNITED STATES PATENT OFFICE

CHARLES D. JOHNSON, OF WORCESTER, MASSACHUSETTS, ASSIGNOR TO JOHNSON STEEL & WIRE COMPANY, INC., OF WORCESTER, MASSACHUSETTS, A CORPORATION OF MASSACHUSETTS

STRIPPER FOR REMOVING COILS OF WIRE FROM A DRAWING HEAD

Application filed February 9, 1931. Serial No. 514,509.

This invention relates to strippers such as are used in wire mills for removing bundles or coils of wire from the drawing heads or drawing blocks.

5 In the manufacture of wire it is customary to draw the wire through dies to reduce it to the proper size and then to wind the drawn wire on a drawing block which is in the nature of a rotary drum. The drawing block 10 usually furnishes the power necessary to draw the wire through the dies. After a sufficient amount of wire has accumulated on any drawing block the coil or bundle of wire is removed from the block. This is commonly done by means of an apparatus termed a "stripper" and the present invention relates to a device of this type.

One of the objects of the invention is to provide a stripper for this purpose which 20 is designed to operate from the outside of the coil of wire, and which, therefore, may be described as an "outside stripper," as distinguished from the stripper which is now commonly used and which operates from the 25 inside of the coils of wire, and which may be referred to as an "inside stripper." One advantage resulting from the use of the outside stripper is that it can be used with a water cooled drawing block without materially reducing the water cooling area.

In order to give an understanding of the invention I have illustrated in the drawings a selected embodiment thereof which will now be described after which the novel features will be pointed out in the appended 35 claims.

Fig. 1 is a side view of a form of stripper embodying my invention, said view showing the stripper open ready to receive the wire 40 bundle;

Fig. 2 shows the stripper closed and in the act of removing a bundle of wire from the block;

Fig. 3 is a top plan view of the stripper 45 shown in in Fig. 2 with a part broken out;

Fig. 4 is a section on the line 6—6, Fig. 2;

Fig. 5 is a section on the line 7—7, Fig. 2;

Fig. 6 is a section on the line 8—8, Fig. 2;

In the drawings 1 indicates a rotary drawing block or drum on which wire 2 is being

wound. It will be understood, of course, that the drum is power driven and in the illustrated embodiment of the invention the drum is a water cooled drum, it having an interior chamber through which water is flowing to 55 prevent the drum from being heated from the heat of the wire as it is wound thereon.

As stated above one purpose of the present invention is to provide a stripper which can be used in connection with a water cooled 60 block without interfering with the water cooling operation by reducing the size of the water chamber and for this purpose the stripper is made to act on the wire bundle from the outside rather than from the inside. 65

A form of stripper embodying my invention is shown in the drawings. This stripper comprises a supporting frame 3 which is formed with a central hub member 4 and supporting arms 5 rigid therewith and extending radially therefrom. The supporting frame also includes a member 6 which is connected to the arms 5 by suitable links 7. The member 6 is shown as having an eye 8 to which a supporting cable or chain 9 may be 70 attached.

Each supporting arm 5 has a stripper arm 10 pivoted to its outer end as at 11. The lower end of each stripper arm is bent inwardly to constitute a wire-engaging finger 12. The upper end of each stripper arm is also bent inwardly as at 13 and is connected by a link 14 to a yoke member 15. The yoke member 15 is swivelled on the upper end of an actuating sleeve 16 which extends through and is 75 slidably mounted in the hub 4. This sleeve 16 is shown as having an annular groove 17 at its upper end in which the yoke 15 is received.

The yoke 15 and sleeve 16 are thus held 80 from movement relative to each other in the direction of the axis of the sleeve but the sleeve is capable of turning in the hub 4 and yoke 15.

With this construction the vertical movement of the sleeve 16 through the hub 4 will 85 operate through the yoke 15 and links 14 to swing the stripper arms 10 about their pivots 11. When the sleeve is in its lowered position shown in Fig. 2 the lower ends of the stripper arms will be spread from each other and 90

said stripper will be in open position. When in this position any lifting force applied to the frame for raising and lowering the stripper will be applied to the stripper arms 5 through the supporting arms 5 and the pivotal connections 11 of said arms with the stripper arms.

When the sleeve is raised through the hub 4 into the position shown in Fig. 6 the lower 10 end of the stripper arms will be moved toward each other and the latter will be in closed position.

The operation of stripping the wire 2 from the drawing block 1 consists in lowering 15 the stripper into the position shown in Fig. 1 while the stripper arms are in open or inoperative position during which operation the fingers 12 at the lower ends of said arms pass down outside of the coil of wire on the 20 drawing block 1, and then closing the stripper arms by moving them into the dotted line position Fig. 2 thereby to introduce the fingers 12 into the horizontal grooves 20 underneath the wire on the block, and thereafter 25 to raise the stripper with the fingers in the closed position as shown in full lines Fig. 2, during which operations the tips of the fingers 12 will move upwardly in the grooves 19 and said fingers will strip the coil 18 of 30 wire from the drawing block. During this stripping operation the lifting force for lifting the stripper arms is applied thereto through the upper ends of the inwardly-directed portions 13 thereof as will be presently explained.

The head 6 is shown as having a locking pin 22 secured thereto axially thereof and this locking pin extends into the sleeve 16 as shown best in Fig. 6. The lower end of the locking 40 pin 22 has a projection or finger 23 extending laterally therefrom through a slot 24 formed in the sleeve 16. This slot has a vertical portion 25 and a horizontal locking portion 26 at its lower end. 27 indicates an arm or handle secured to the sleeve 16 and by which the latter may be turned.

The lower end of the sleeve is shown as closed by a plug or closure 28 and the latter carries a stop screw 29 which is adjustably 50 mounted in the closure 28 and may be locked in adjusted position by a set nut 30.

The closing of the stripper arms is accomplished by the engagement of the stop screw 29 with the upper end 31 of the spindle of the drum or drawing block 1 during the lowering of the stripper. Fig. 1 shows the stripper, with the stripper arms open, being lowered into position to engage the wire and with the stop screw 29 about to engage 60 the upper end 31 of the block spindle. During further lowering movement the screw 29 engages the upper end 31 of the spindle thereby preventing further downward movement of the sleeve 16 and as the lowering of 65 the supporting frame of the stripper con-

tinues the hub 4 and supporting arms 5 will move downwardly relative to the sleeve 16, or in other words, the sleeve 16 will have an upward movement relative to the supporting frame. This relative movement operates through the lug 15 and arms 14 to close the stripper arms into the position shown in dotted lines Fig. 2 and during this closing movement the fingers 12 enter the horizontal grooves 20 and assume positions underneath the wire which has been wound on the drawing block.

When the stripper arms are fully closed the locking projection 23 will have been 80 carried to the lower end of the slot 24 and the operator then grasps the handle 27 and turns the sleeve to carry the projection 23 into the horizontal locking portion 26 of the slot 24 as indicated in Fig. 2. This locks the sleeve 16 in its raised position relative to the hub 4 and thus locks the stripper arms in their closed relation. When the stripper arms are thus in their closed position the lifting force required to raise the stripper and the wire bundle is transmitted from the lifting cable 9 to the locking pin 22 and through the projection 23 and slot 26 to the sleeve 16 and from the sleeve 16 through the links 14 to the upper ends of the stripper arms so that the stripper arms are supported 90 from their upper ends and are thus held in their closed relation.

I claim:

1. A stripper for stripping wire bundles from a drawing block, said stripper comprising a supporting frame having a central hub and radially-extending arms, stripper arms pivotally mounted to said radially-extending arms, each stripper arm having at its lower end an inwardly-directed finger, a sleeve member extending through and slidably mounted in said hub, links connecting the upper ends of said stripper arms to said sleeve, movement of the sleeve through the hub swinging the stripper arms from inoperative to operative position, and means to lock said arms in their operative position.

2. A stripper for stripping wire bundles from a drawing block, said stripper comprising a supporting frame having a central hub and radially-extending arms, stripper arms pivotally mounted to said radially-extending arms, each stripper arm having at its lower end an inwardly-directed finger, a sleeve member extending through and slidably mounted in said hub, links connecting the upper ends of said stripper arms to said sleeve, upward movement of said sleeve through said hub swinging said arms from their inoperative to operative position, and means to lock the sleeve in its raised position.

3. A stripper for stripping wire from a drawing block, said stripper comprising a supporting frame having a central hub, ra-

dially-extending supporting arms rigid therewith and a head connected to said arms and provided with means for the attachment of a suspending cable, a stripper arm pivotally connected to the outer end of each supporting arm, each stripper arm having an inwardly-directed finger at its lower end, a sleeve slidably mounted through said hub, means connecting the upper end of each stripper arm to said sleeve, upward movement of the sleeve through the hub operating to swing the stripper arm from open to closed position, a locking pin secured to said head and extending into said sleeve, and means co-operating with said pin and sleeve to lock the latter in raised position.

4. A stripper for stripping wire from a drawing block, said stripper comprising a supporting frame having a central hub, radially-extending supporting arms rigid therewith and a head connected to said arms and provided with means for the attachment of a suspending cable, a stripper arm pivotally connected to the outer end of each supporting arm, each stripper arm having an inwardly-directed finger at its lower end, a sleeve slidably mounted through said hub, means connecting the upper end of each stripper arm to said sleeve, upward movement of the sleeve through the hub operating to swing the stripper arm from open to closed position, a locking pin secured to said head and extending into said sleeve, the latter having a vertical slot with an offset portion and a projection carried by said locking pin and operating in said slot to lock the sleeve in raised position.

In testimony whereof, I have signed my name to this specification.

CHARLES D. JOHNSON.
